Primary Examiner — Stacia Cadmus(74) *Attorney, Agent, or Firm* — Wood Herron & Evans LLP(57) **CLAIM**

The ornamental design for a wheel, as shown and described.

DESCRIPTION

FIG. 1 is a left front perspective view of a wheel according to the invention.

FIG. 2 is a front view of the wheel shown in FIG. 1; and, FIG. 3 is a right side view of the wheel shown in FIG. 1, the left side view being a mirror image thereof.

The broken line showing of the rear of the rim, the valve stem hole, the bolt holes and the center hole in the central hub area is included for the purpose of illustrating environmental subject matter and forms no part of the claimed design.
